FLASHLIGHT

Charles E. Wohler and Lewis G. Sherwood, Niagara Falls, N. Y., assignors to Niagara Searchlight Company, Inc., Niagara Falls, N. Y., a corporation of New York

Application June 28, 1944, Serial No. 542,517

3 Claims. (Cl. 240—10.63)

1

This invention relates to a flashlight and more particularly to a novel and attractive form of flashlight adapted for use in the home.

One of the principal objects of the present invention is to provide a novel flashlight in which the switch is readily accessible and conveniently turned on, the operating member of the switch being a bail-like handle for the flashlight so that when the flashlight is lifted by the handle the flashlight is turned on, thereby rendering the flashlight very convenient in use.

Another object is to provide such a flashlight in which the casing is of a novel two-part construction and which can be made of a synthetic plastic in any color and of highly ornamental and attractive appearance.

Another object is to provide a simple and inexpensive means for latching the two parts of the casing together and which at the same time readily permit of separating the casing to replace the batteries or to replace the flashlight bulb.

Other objects are to provide such a flashlight which is extremely low in cost and simple and rugged in construction so as to stand up under conditions of severe and constant use without getting out of order or requiring repairs.

In the accompanying drawings:

Fig. 1 is a front elevation of a flashlight embodying the present invention.

Fig. 2 is a rear elevation thereof.

Fig. 3 is a vertical central fore-and-aft section, taken on line 3—3, Fig. 1.

Fig. 4 is a vertical, central, transverse section, taken generally on line 4—4, Fig. 3.

Fig. 5 is a bottom plan view of the top section or part of the two-part housing or casing of the flashlight.

Fig. 6 is a top plan view of the bottom section or part of the flashlight casing.

Fig. 7 is a view similar to Fig. 2 and showing a modified form of latching means for holding the two sections of the casing together.

Fig. 8 is a fragmentary vertical section, taken on line 8—8, Fig. 7.

The flashlight comprises a body or casing 10 which is composed of an upper section 10a and a lower section 10b. Each of these sections is of generally rectangular box-like form and the two sections jointly provide a rectangular casing having a top 11, end walls 12, a bottom wall 14, a front wall 15 and a rear wall 16. At the parting line between the two sections 10a and 10b the sections are preferably provided with outwardly projecting mating ribs or flanges 18, for strength,

2

and the section 10b is shown as provided with flanges 19 fitting into recesses 20 so as to insure proper registry of the two sections when they are brought together.

5 The front wall 15 jointly provided by the two sections 10a and 10b, is provided with a forwardly projecting external annular flange 21, the parting line between the two sections 10a and 10b extending through the axis of this flange 21. 10 Against the forward end of this flange 21 is fitted the radially outward projecting rim of a metal reflector 22, this reflector extending into the casing and having a threaded neck 23 into which is screwed the base of a flashlight bulb 24, the 15 sheath of this base having electrical contact with the reflector 22 through the neck 23. Against the radially projecting flange of the reflector 22 is arranged a disk 26 of transparent material, preferably a synthetic plastic, which is not easily 20 broken and this disk or lens 26 and also the reflector 22 are held in centered relation with the flange 21 by an annular ring or rim 28 which is screwed on the externally threaded annular flange 21 and which is L-shaped in cross section 25 to hold the rims of the lens 26 and reflector 22 tightly against the end of the threaded annular flange 21. It will also be seen that this internally threaded ring 28 serves to hold the two sections 10a and 10b of the casing together at the front 30 side thereof.

At the rear side of the flashlight the two sections 10a and 10b of the casing are preferably held together by a latching mechanism which is preferably constructed as follows:

35 In axial alignment with the reflector 22 and its bulb 24 the section 10b is provided with an upward semi-circular extension 30 which fits into a corresponding recess 31 in the section 10a. At this place the lower section 10b is also formed to 40 provide a rearwardly projecting boss 32 to which is rotatably secured, by means of a rivet 33, a disk 34. This disk has a forwardly projecting flange 35, this flange 35 being adapted to engage the rear wall 16 of the casing and preferably 45 being knurled or roughened so that it can conveniently be turned by hand. At one side of the disk 34 this rim 35 is broken away so as to provide an opening 36 through the rim 35 at this side of the disk.

50 Above the upward extension 30 of the lower section 10b, the upper section is provided with a rearwardly extending boss 38 the upper side of which is curved to conform to the flange 35 of the disk 34 which embraces this boss. The width of this boss 38 is approximately equal to the

width of the opening 36 in one side of the rim 35 of the disk 34. It will therefore be seen that upon turning the disk 34 so that the opening 36 in its rim 35 registers with the rearwardly projecting boss 38 of the section 10a, the boss 38 can be withdrawn upwardly through the opening 36 thereby to permit the separation of the two halves of the casing, it being assumed, of course, that the ring 28 has been first removed. Similarly, upon turning the disk 34 so that the solid part of the rim 35 engages with the boss 38, the two halves of the casing are latched together.

Within the casing are arranged two flashlight batteries 40 and 41, these batteries being arranged inverted with respect to each other. The positive contact of the battery 40 engages a spring contact 42, this spring contact 42 being mounted on a metal strip 43 which is secured to the underside of the top wall 11 of the casing in any suitable manner and which has a spring contact 44 extending downwardly along the side wall 12 of the casing adjacent the battery 40. Similarly, the negative contact of the battery 41 engages a spring contact 45 which is mounted on a metal strip 46 secured to the underside of the top wall 11 of the casing and formed to provide a depending spring contact 48 arranged along that side wall 12 of the casing adjacent to the battery 41. Adjacent each of the spring contacts 44 and 48 the side walls 12 of the casing are each provided with an internal vertical guideway 49 in which the side legs 50 of a metal bail-like handle 51 slide, these side legs extending up through openings 52 in the top wall 11 of the casing. The handle 51 can be pushed inwardly until its side legs 51 engage the bottom of the guideways 49, as shown by dotted lines in Fig. 4, and the handle 51 can be pulled out to the full line position shown in Fig. 4 in which latter position contacts 53 on the side legs 50 of the handle 51 engage the spring contacts 44 and 48.

The negative contact of the battery 40 engages a metal plate 56 secured to the bottom wall 14 of the casing in any suitable manner and having an upwardly projecting spring contact 58 formed integrally therewith and arranged to engage the contact 59 at the rear end of the electric light bulb 24. Similarly, the positive contact of the battery 41 engages a plate 60 secured to the bottom wall 14 of the casing and which has an integral upwardly projecting spring contact 61, this contact engaging the metal reflector 22.

When the user desires to turn on the flashlight, he lifts it by the handle 51. The weight of the batteries and casing of the flashlight causes the legs 50 of this handle to slide upwardly in the internal guideways 49 for these legs, the handle thereby moving outwardly relatively to the casing to the full line position shown in Fig. 4. At the outer extremity of this movement the contacts 53 on the legs 50 of the handle engage the spring contacts 44 and 48. A circuit is thereby established from the positive terminal of the battery 40, through the spring contact 42, supporting plate 43, spring contact 44, adjacent contact 53, handle 51, spring contact 48, supporting plate 46, spring contact 45, negative terminal of battery 41, supporting plate 60, spring contact 61, reflector 22, bulb 24, spring contact 58 and supporting plate 56 to the negative side of the battery 40.

To turn the battery off the user pushes the handle inwardly to the dotted line position shown in Fig. 4, this breaking the engagement between the contacts 53 of the handle 51 and the spring contacts 44 and 48 so as to break this circuit.

When the user desires to, say, replace the batteries 40 and 41 he first removes the ring 28 which holds the lens 26 and reflector 22 in position, the removal of this ring permitting the separation of the two sections 10a and 10b of the battery casing at the front side of the flashlight. He then turns the disk 34 so that the opening 36 in its rim or flange 35 registers with the boss 38. This boss can thereby be removed upwardly through the opening or mutilated part 36 of the flange 35 so as to permit the complete separation of the two sections 10a and 10b of the casing. Since the switch mechanism is completely carried by the section 10a of the casing and since the connectors 15 comprise the permanent plates 43, 46, 56 and 60 with their spring contacts, it will be seen that the separation of the two halves 10a and 10b of the casing exposes the batteries 40 and 41 for direct removal and replacement thereby greatly simplifying this operation.

In the modified form of the latch means shown in Figs. 7 and 8, and which replaces the disk 34, the section 10a of the casing is provided on its rear wall 16 with a lug 65 carrying a loop or ring 66, the ends of which are pivotally secured in the lug 65. The lower part of this loop is arranged to snap into an undercut recess 68 provided in the lug or boss 69 formed integrally with the lower section 10b of the casing. It will be seen that in operating the latch shown in Figs. 7 and 8 it is merely necessary to force the ring or loop 66 out of the undercut recess 68 to permit the separation of the two halves 10a and 10b of the casing in the same manner as with the form of the invention shown in Figs. 1-6.

From the foregoing it will be seen that the present invention provides a simple and novel form of flashlight which is particularly adapted for home use in that it is turned on and off by the simple expedient of lifting and lowering the handle, the handle being of large size so that it can be conveniently gripped in the dark. It will further be seen that the two-part construction of the casing permits of ready access to the batteries for their replacement and that the construction of the casing is rugged and at the same time inexpensive so that the flashlight can be produced at low cost.

We claim as our invention:

1. A flashlight, comprising a casing adapted to contain a battery and comprising two generally counterpart cup-shaped sections fitted together, an annular flange projecting outwardly from said casing and jointly provided by said sections, a reflector arranged within said annular flange, an electric light bulb mounted in said reflector, a ring embracing said annular flange and holding said sections together, a manual switch carried by one of said sections, means connecting said switch in circuit with said electric light bulb and battery, and latch means connecting said sections together on the side of said casing opposite said flange, and comprising a disk rotatably mounted on the adjacent wall of one of said casing sections in generally axial alinement with said annular flange, a rim projecting forwardly from said disk into engagement with said adjacent wall and having an opening at one side, and a boss provided on the adjacent wall of the other of said casing sections and embraced by the rim of said disk, said boss being of such size as to pass through said opening when brought into register therewith.

2. A flashlight, comprising a casing adapted to contain a pair of elongated cylindrical batter-

ies having terminals at their opposite ends, comprising two generally counterpart cup-shaped sections having mating edges and each adapted to embrace the corresponding ends of said batteries with said mating edges extending transversely of the axes of said batteries, an annular flange projecting outwardly from said casing with its axis generally perpendicular to the axes of said batteries and jointly provided by said sections, a metal reflector arranged within said annular flange and extending into the interior of said casing, an electric light bulb mounted in said reflector and having one contact in electrical connection therewith, means releasably holding said sections together, and means for connecting said batteries in circuit with said light bulb, comprising a metal plate in electrical engagement with each terminal of each of said batteries and secured to the adjacent section of the casing, a spring contact integral with one of said plates and directly contacting said metal reflector, a spring contact integral with the companion plate in the same section as said one of said plates and directly engaging the other contact of said bulb, and manual switch means mounted on the other section of said casing for closing the circuit between the other plates to establish a series circuit between said batteries and said light bulb comprising a spring contact integral with each of said other two plates and arranged adjacent a corresponding one of the opposite side walls of said other section, a bail-like metal handle by which said casing is transported and having side legs mounted in internal guideways provided in said opposite side walls of said other section for vertical sliding movement relative thereto, and a contact surface on each of said legs and adapted to directly engage the spring contacts on said other two plates when said handle is moved outwardly relative to said casing.

3. A flashlight comprising a casing of dielectric material and having a top wall, a bottom wall and side walls connecting said top and bottom walls, a metal reflector mounted on one of said side walls and extending into the interior of said

- casing, an electric light bulb mounted in said reflector and having one contact in electrical connection therewith, a pair of spaced metal plates in said casing secured to the bottom wall thereof, a metal contact on one of said plates engaging said reflector, a metal contact on the other of said plates and engaging the other contact of said bulb, a second pair of spaced metal plates in said casing secured to the top wall thereof, a pair of elongated electrical battery cells arranged vertically side by side within said casing and having terminals at their opposite ends each in contact with a corresponding one of said plates, and manual switch means for closing the circuit between said second pair of plates to establish a series circuit through said bulb and cells, comprising a U-shaped metal handle having vertical end legs, the opposite side walls of said casing being internally provided with a pair of vertical guideways terminating in openings through said top wall and said guideways and openings slidably receiving said vertical legs, an electrical contact on each of said legs and projecting in opposed relation to each other, and a spring contact on each of said second pair of plates and arranged to engage the contact on the corresponding one of said legs in the elevated position of said U-shaped handle, said U-shaped handle being thereby included in the circuit of said bulb and cells in the closed position thereof.
